HEAT ENGINE

Erwin G. Baker, Indianapolis, Ind.

Application December 30, 1944, Serial No. 570,599

12 Claims. (Cl. 123—43)

1

This invention relates to an engine operating on what might be called a delayed two-cycle principle. A primary advantage of the invention is that the structure embodying it may be made exceedingly simple, without valves and the attendant valving gear, crank shaft, and any elaborate oiling system. A still further important advantage of the invention is that a continuous flow of power is delivered at the final drive shaft and yet each piston and cylinder has a "rest" period between the firing of the charge in the particular cylinder, although all of the cylinders employed in the engine will fire once for each revolution of the drive shaft.

A further important object of the invention is to provide an exceedingly high power output per unit weight with such an overlapping of power impulses that the final drive is by a substantially constant torque.

These and many other objects and advantages of the invention will become apparent to those versed in the art in the following description of one particular form of the invention more or less diagrammatically illustrated in the accompanying drawings, in which

Fig. 1 is a view primarily in central vertical longitudinal section through a structure embodying the invention;

Fig. 2, a detail in transverse section through an oil supply groove in a piston on the line 2—2 in Fig. 1;

Fig. 3, a detail in vertical transverse section on the line 3—3 in Fig. 1 through the connection between a piston and a drive bar;

Fig. 4, a vertical transverse section on the line 4—4 in Fig. 1;

Fig. 5, a horizontal transverse section on the line 5—5 in Fig. 1;

Fig. 6, a top plan view of the engine in partial section; and

Fig. 7, a view in front end elevation in partial section.

Like characters of reference indicate like parts throughout the several views in the drawings.

In the showing herein, it is to be understood that in production, refinements will be employed particularly in regard to bearings, mounting means of the various elements, and the like. Referring to the drawings, a suitable housing 10 is formed to carry therein an L-shaped crank 11 in a stationary manner, to have a vertically disposed leg thereof extending upwardly through the housing 10, and a horizontally disposed leg extending around and horizontally toward the rear of the housing 10. This crank 11 is made

2

out of suitable material which would be quite rigid in respect to bending from the right angle formed by the vertical and horizontal legs thereof.

The upwardly directed leg of the crank 11 is fixed in position centrally through a top plate 12 carried in turn by the housing 10. For vertical adjustment of the crank 11 the upper end of the crank 11 may be threaded to be lowered or raised by the turning of the adjusting nut 13 which screw threadedly engages externally of the crank end and bears by its under side against a seat on the top side of the plate 12. Then any suitable means is provided to prevent rotation of the crank 11 about its vertical axis, such means herein being shown as a set screw 14 passing through an upturned portion of the plate 12 and engaging the crank 11 therewithin.

An upper barrel 15 is provided to have an axial bore therethrough to fit around the upturned leg of the crank 11 with a close-running fit, any suitable bearing surface or surfaces being employed therebetween. A collar 16 fixed around the crank 11 supports the barrel 15 from its underside so as to position it in respect to its elevation along the upturned arm of the crank 11. A spacing collar 17 is interposed between the under side of the plate 12 and the top of the barrel 15 so as to maintain that elevation of the barrel 15. The barrel 15 is preferably provided with some external cooling means herein shown as a plurality of fins 18 extending therearound and the upper portion of the housing 10 is properly apertured to provide for air passage through the housing and around and across the fins 18.

Radially spaced outward from the axis of the barrel 15 are a plurality of cylinders 19, herein shown as eight in number, each equally spaced apart circumferentially one from the other, the axes of the cylinders being parallel with the central axis of the barrel 15. These cylinders 19 open through the under face of the barrel and are closed at their upper ends with some fuel igniting means being inserted therethrough, such as a spark plug 20. The barrel 15 is further provided with transverse bores 21 radially extending from the central bore of the barrel opening into each cylinder and leading from each cylinder to finally open through the outer cylindrical wall 50 of the barrel, these bores 21 being aligned to have their axes in a common transverse plane toward the lower end of the barrel 15.

The upper leg at least of the crank 11 is hollow, and is provided with a port 22 to register with the inner ports of the bores 21 as the barrel 15

may be revolved around the crank arm. The housing 10 engages the lower circumferential wall of the barrel 15 with a sliding fit so that the outer ends of the bores 21 are normally closed off, Fig. 5, until those ends register successively with an elongated port 72 on the inner end of a bore 23 passing through the housing 10 and radially aligned.

On the horizontally disposed leg of the crank 11 is revolubly mounted a barrel 24 fixed against longitudinal travel thereon by any suitable means, such as a collar 25 on the crank 11 and an outer frame 26 supported by the housing 10. This barrel 24 is interconnected in a driving manner with the barrel 15 through bevel gears 27 and 28 on the lower and inner ends respectively of the barrels 15 and 24, these gears being in constant mesh and being formed, in the present showing, by teeth cut in the barrels themselves. The barrel 24 has a plurality of cylinders 29, the number of these cylinders being in all cases equal to the number of the cylinders 19 provided in the upper barrel 15, and these cylinders 29 are radially spaced from the axis of the barrel 24 an equal distance as well as being equally spaced apart circumferentially to have the axes of these cylinders 29 parallel to the central axis of the barrel 24.

In each cylinder 29 of the barrel 24 is slidably mounted a drive bar 30, each of these bars being identical and being externally cylindrical to have a sliding fit in its respective cylinder 29.

Then in each of the cylinders 19 of the barrel 15 is slidably carried a piston 31 to interconnect by its lower end with the end of the drive bar 30 respectively extending from the lower barrel 24. While it is possible to make an integral connection between the piston 31 and the drive bar 30 in each case, it is preferable to make a rockable connection to allow for minute errors in machine work, as well as variations occurring in expansion and contraction between the various parts. One form of such a connection between these members is illustrated primarily in Fig. 3, wherein an ear 32 extends from the bar 30 to have parallel vertical faces across which slidably extend the downwardly directed legs 33 and 34 from the piston 31 and then a piston pin 35 is carried through the leg 33, the ear 32, and the other leg 34 to pin those two members 30 and 31 together in a rockable manner.

Both the drive bars 30 and the pistons 31 are made out of a highly heat-resisting material, such as may be obtained commercially under the trademark "Graphitar" which is used in electric furnaces. This particular material is not only highly heat-resisting, but its inherently contained graphite affords a substantially frictionless surface bearing against the cylinder walls 29 and 19 in each instance. As is indicated in Fig. 1, both the drive bar 30 and the piston 31 in each instance has substantially the same diameter throughout its length so that those two members are axially aligned in respect to their receiving cylinders in any and all positions they may take in respect thereto.

To further reduce friction and aid in cooling as well, an oil sump 36 is provided in the lower part of the housing 10 particularly under the barrel 24, and a passageway 37 leads from the outer circumferential face of the barrel 24 inwardly to open into a cylinder 29 in each one thereof. Preferably this passageway 37 is located toward the inner end of the barrel 24 through which the cylinders 29 open, as indicated

in Fig. 1. The drive bar 30 in each instance is provided with a bore 38 therethrough registering by its outer end with an opening 39 in the piston pin 35, from which bores 40 and 41 lead upwardly through the respective legs 33 and 34 to a transverse passageway 42 in turn opening into a central bore 43 leading upwardly through the piston 31 to discharge laterally toward the top end thereof into an oil groove 44 by means of a plurality of transverse passageways 45. This oil groove 44 is located below piston rings 46 carried around the upper end portion of the piston 31. Preferably, to relieve and permit return flow of the oil back into the lower sump 36, each piston 31 is provided with a spiral groove 47 leading from below the oil groove 44 so as to carry the oil back down around the piston 31 and discharge it from its lower end to allow it to drop back into the lower portion of the housing 10. This oil return means plus the scraping of the rings 46 above prevents excess oil from flowing past the upper end of the piston.

The lengths of the cylinders 19 and 29 and of the drive bars 30 and pistons 31 are so proportioned that when one cylinder 29 is at its lowermost position, Fig. 1, and a cylinder 19 at its extreme right hand position, the piston 31 will be at its lower limit of travel with the rings 46 still well within the cylinder 19, while at the same time the drive bar 30 will be in its most extended position from that lower cylinder 29 and still have a sufficient length of the bar 30 within the cylinder 29 as to prevent "cocking" of the bar in the cylinder.

To supply fuel to the various cylinders 19, any suitable fuel supply means may be employed, a simple form being herein shown as by supercharged carburation of a volatile fuel. The barrel 24 is provided with any suitable drive means, such as a worm 48 therearound meshing constantly with a worm wheel 49 fixed on a shaft 50 that extends upwardly into a supercharger 51, the detail construction of which is not herein shown but may be of the standard design now commercially employed. Mounted directly over the supercharger is a carburetor 52 having its discharge through a pipe 53 centrally into the supercharger 51. An air cleaner 54 is mounted on a pipe 55 which discharges into the carburetor 52. The discharge of the supercharger 51 is taken by a pipe 56 which leads therefrom and around into the upper open end of the crank 11, Fig. 1. The only outlet from the crank 11 to discharge the fuel mixture forced therein is through the port 22.

Now when the barrel 15 is revolved about the crank 11 to start operation initially, such as by starting motor 57, the innermost ports of the transverse bores 21 will register one after another with this port 22 to allow the mixture compressed therein to flow into the cylinder 19. As is the usual practice in a two-cycle system, the upper end of the piston 31 in each instance is preferably provided with a baffle 58 extending diametrically across the piston and carried thereabove a distance greater than the diameter of the passageway 21, whereby the gases coming into the cylinder 19 from the port 22 will be directed upwardly into the cylinder 19 to not only flow to the top end thereof, but also to effect a scavenging action by forcing air and exhaust gases when in operation outwardly from the opposite side of the baffle 58 through the passageway 21 and out through the housing passageway 23. As the cylinder 19 thus charged with the combustible mixture travels on around to close off the

particular transverse bore 21, the piston 31 in that cylinder rises by reason of the drive bar 30 being simultaneously lifted on account of the rotary travel of the barrel 24. This last action of the bar forces the piston 31 upwardly in the cylinder 19 to compress that fuel mixture, and as the piston 31 approaches its upper limit of travel, or slightly thereafter in accordance with the predetermined timing desired, the spark plug 20 then being in the position on the extreme left hand side of the crank 11, as indicated in Fig. 1, will be energized by coming under the distributor point 59 insulately carried by the plate 12 and in electrical circuit with a distributor head 60 mounted in the usual manner on a generator 61 in turn driven through the spur gear 62 in constant mesh with the ring gear 63 fixed around the outer end of the barrel 24. In this regard it is understood that the usual ignition system is employed whereby the transformer coil 64, herein shown mounted on the generator 61, transforms the generator current into the necessarily high ignition voltage.

That same action follows for each of the pistons 31, the charge in each succeeding cylinder 19 being ignited as rapidly as the next succeeding spark plug 20 comes around past the distributor point 59. Then the piston 31 in each instance is driven downwardly from its uppermost position to in turn through its connected drive bar 30 revolve the barrel 24 to continue the operation of the engine. It is to be observed that while each cylinder 19 fires once each every revolution of the barrel 15, there is a considerable relative delay in the firing of each cylinder as between the time the one spark plug 20 reaches the firing position under the point 59 and then returns again, during which period the particular cylinder 19 has been recharged and exhausted and then that charge compressed.

Any suitable drive hookup may be employed to take power from the driven barrel 24, one such form being a drive shaft 65 having a pilot end 66 carried in a suitable bearing within the rear end of the crank 11, and another portion of that shaft 65 supported by the frame 26 in such manner that not only is the shaft 65 adequately supported, but also that shaft through its bearing in the frame 26 will tend to give support to the horizontal leg of the crank 11. Then a clutch member 67 drivingly mounted on the shaft 65 to slide longitudinally therealong may frictionally interconnect the shaft 65 with the barrel 24 by pushing the member 67 up against the barrel 24 or a suitable friction member 68 interposed therebetween.

As the barrel 24 is turned during the normal operation, the passageway 37 in each instance will be submerged in the oil carried in the sump 36 not only to provide normal flow of the oil through that passageway into the cylinder 29, but also to afford a relief of a partial vacuum which may be set up in the cylinder 29 as the drive bar travels outwardly, although this change in pressure within the cylinder 29 will tend to be prevented by reason of the opening of the oil lines through the bar 30 and the piston 31. In any event, return travel of the drive bar 30 inwardly within the cylinder 29 past the passageway 37 to close off that passageway will cause the oil flowing into the cylinder 29 to be forced through those oil lines provided to cause the oil to discharge into the piston groove 44 as above indicated. The rapid travel of the barrel 24 will also tend to cause a "scooping" action of the oil into the passageway 37 in each instance, as well as to throw

the oil about the various members exposed within the housing 10.

Since there is substantially a continuous flow of power, the compression ratio in each power cylinder may be carried quite high as compared to the usual two or four cycle type of engine. The mass of the barrel 24 serves admirably as a fly wheel in addition to its primary purpose of translating the reciprocating motion of the piston 31 into rotary motion in the absence of a crankshaft and the heretofore usual connecting rods.

While I have herein shown and described my invention in the one particular form, as previously indicated, mechanical changes may be employed in many instances without departing from the spirit of the invention, and I therefore do not desire to be limited to that precise form beyond the limitations as may be imposed by the following claims.

I claim:

1. An engine comprising a rotatable barrel having a plurality of cylinders therein with parallel axes centered on a common circle about the axis of said barrel; a piston in each cylinder; a second barrel rotatable about an axis normal to the axis of said first barrel; gear means drivingly interconnecting said barrels; said second barrel having a plurality of openings therein from one end equal in number to that of said cylinders; members slidably fitting through said openings; and means interconnecting said pistons to said members, one piston to each member.
2. An engine comprising a rotatable barrel having a plurality of cylinders therein with parallel axes centered on a common circle about the axis of said barrel; a piston in each cylinder; a second barrel rotatable about an axis normal to the axis of said first barrel; gear means drivingly interconnecting said barrels; said second barrel having a plurality of openings therein from one end equal in number to that of said cylinders; members slidably fitting through said openings; and means interconnecting said pistons to said members, one piston to each member; said last interconnecting means comprising a rockable joint.
3. An engine comprising a driving rotatable barrel having a plurality of cylinders therein spaced apart and outwardly from the rotation axis of the barrel; a piston in each of said cylinders; a second barrel rotatable on an axis substantially at right angles to the rotation axis of said first barrel; a plurality of cylinders in said second barrel equal in number to that of the cylinders in the first barrel; a slide bar in each second barrel cylinder; means interconnecting each bar to a respective piston; fuel conducting means axially entering said first barrel and having a discharge port; said first barrel having a passageway extending transversely thereof to have an inner port registrable upon barrel rotation with said fuel discharge port, and having another port opening into a cylinder, one passageway being provided for each cylinder; said first barrel being further provided with an exhaust passageway from each cylinder with an exhaust port; a housing about said barrel at least in the region of said fuel and exhaust passageways; said housing having an exhaust port and said barrel exhaust ports being registrable therewith one after another.
4. An engine comprising a driving rotatable

barrel having a plurality of cylinders therein spaced apart and outwardly from the rotation axis of the barrel; a piston in each of said cylinders; a second barrel rotatable on an axis substantially at right angles to the rotation axis of said first barrel; a plurality of cylinders in said second barrel equal in number to that of the cylinders in the first barrel; a slide bar in each second barrel cylinder; means interconnecting each bar to a respective piston; fuel conducting means axially entering said first barrel and having a discharge port; said first barrel having a passageway extending transversely thereof to have an inner port registerable upon barrel rotation with said fuel discharge port, and having another port opening into a cylinder, one passageway being provided for each cylinder; said first barrel being further provided with an exhaust passageway from each cylinder with an exhaust port; a housing about said barrel at least in the region of said fuel and exhaust passageways; said housing having an exhaust port and said barrel exhaust ports being registerable therewith one after another; a fuel igniter in each cylinder; a relatively fixed electrode in circuit with a source of current; and an electrode on each igniter revolute in the path of said fixed electrode.

5. An engine comprising an L crank fixed in position; a barrel revolvably mounted on one leg of the crank; a second barrel revolvably mounted on the other leg of the crank; each of said barrels being provided with a common number of cylinders opening at adjacent ends of the barrels; a piston in each cylinder of each barrel interconnected at substantially right angles one with another; fuel supply means having a discharge port; a transverse passageway entering each cylinder of said first barrel and having a port registerable once each barrel revolution with said fuel port; a relatively stationary housing member fitting around said first barrel and having an exhaust port; said first barrel having an exhaust passageway from each cylinder with a discharge port positioned to register with said housing port once each barrel revolution; fuel igniter means in each cylinder; an electrode extending externally of each igniter; a relatively fixed electrode past which said igniter electrodes travel; and a source of current interconnected with said electrodes.

6. An engine comprising an L crank fixed in position; a barrel revolvably mounted on one leg of the crank; a second barrel revolvably mounted on the other leg of the crank; each of said barrels being provided with a common number of cylinders opening at adjacent ends of the barrels; a piston in each cylinder of each barrel interconnected at substantially right angles one with another; fuel supply means having a discharge port; a transverse passageway entering each cylinder of said first barrel and having a port registerable once each barrel revolution with said fuel port; a relatively stationary housing member fitting around said first barrel and having an exhaust port; said first barrel having an exhaust passageway from each cylinder with a discharge port positioned to register with said housing port once each barrel revolution; fuel igniter means in each cylinder; an electrode extending externally of each igniter; a relatively fixed electrode past which said igniter electrodes travel; and a source of current interconnected with said electrodes; an oil sump through which said second barrel travels; means conducting oil from the sump into the second barrel cylinders; and oil

conducting means in the cylinders of both barrels and across their interconnections.

7. An engine comprising an L crank fixed in position; a barrel revolvably mounted on one leg of the crank; a second barrel revolvably mounted on the other leg of the crank; each of said barrels being provided with a common number of cylinders opening at adjacent ends of the barrels; a piston in each cylinder of each barrel interconnected at substantially right angles one with another; fuel supply means having a discharge port; a transverse passageway entering each cylinder of said first barrel and having a port registerable once each barrel revolution with said fuel port; a relatively stationary housing member fitting around said first barrel and having an exhaust port; said first barrel having an exhaust passageway from each cylinder with a discharge port positioned to register with said housing port once each barrel revolution; fuel igniter means in each cylinder; an electrode extending externally of each igniter; a relatively fixed electrode past which said igniter electrodes travel; and a source of current interconnected with said electrodes; said fuel supply means comprising a passageway through at least one of said crank legs, and said fuel discharge port being through a wall of that leg.

8. An engine comprising an L crank fixed in position; a barrel revolvably mounted on one leg of the crank; a second barrel revolvably mounted on the other leg of the crank; each of said barrels being provided with a common number of cylinders opening at adjacent ends of the barrels; a piston in each cylinder of each barrel interconnected at substantially right angles one with another; fuel supply means having a discharge port; a transverse passageway entering each cylinder of said first barrel and having a port registerable once each barrel revolution with said fuel port; a relatively stationary housing member fitting around said first barrel and having an exhaust port; said first barrel having an exhaust passageway from each cylinder with a discharge port positioned to register with said housing port once each barrel revolution; fuel igniter means in each cylinder; an electrode extending externally of each igniter; a relatively fixed electrode past which said igniter electrodes travel; and a source of current interconnected with said electrodes; said fuel supply means comprising a passageway through at least one of said crank legs, and said fuel discharge port being through a wall of that leg; said one leg of the crank having a passageway therethrough leading from said fuel supply means; and said fuel supply discharge port being in said first leg communicating with said passageway therein; and means creating atmospheric or above pressure in said leg passageway.

9. In an engine, a pair of barrels one rotatably mounted on an axis at substantially right angles with the axis of the other; each of said barrels having a plurality of cylinders therein whose axes are respectively parallel to their barrel axes; pistons in all of said cylinders; means interconnecting one piston of one barrel with one piston of the other barrel consecutively therearound whereby movement of the pistons in one barrel will tend to revolve the other barrel through the interconnecting pistons; one of said barrels being provided with transverse passageways opening into its cylinders; fuel conducting means having a port registerable with said passageways consecutively upon rotation of said one

barrel; said one barrel also having an exhaust passageway from each of its cylinders; and fuel igniting means operable in each of said one barrel cylinders once each barrel revolution.

10. An engine comprising an L crank fixed in position; a barrel revolvably mounted on one leg of the crank; a second barrel revolvably mounted on the other leg of the crank; each of said barrels being provided with a common number of cylinders opening at adjacent ends of the barrels; a piston in each cylinder of each barrel interconnected at substantially right angles one with another; fuel supply means having a discharge port; a transverse passageway entering each cylinder of said first barrel and having a port registerable once each barrel revolution with said fuel port; a relatively stationary housing member fitting around said first barrel and having an exhaust port; said first barrel having an exhaust passageway from each cylinder with a discharge port positioned to register with said housing port once each barrel revolution; fuel igniter means in each cylinder; an electrode extending externally of each igniter; a relatively fixed electrode past which said igniter electrodes travel; and a source of current interconnected with said electrodes; said fuel supply means comprising a passageway through at least one of said crank legs, and said fuel discharge port being through a wall of that leg; said one leg of the crank having a passageway therethrough leading from said fuel supply means; and said fuel supply discharge port being in said first leg communicating with said passageway therein; and means creating atmospheric or above pressure in said leg passageway; and gear means drivingly interconnecting said barrels.

11. An engine comprising an L crank fixed in position; a barrel revolvably mounted on one leg of the crank; a second barrel revolvably mounted on the other leg of the crank; each of said barrels being provided with a common number of cylinders opening at adjacent ends of the barrels; a piston in each cylinder of each barrel interconnected at substantially right angles one with another; fuel supply means having a discharge port; a transverse passageway entering each cylinder of said first barrel and having a port registerable once each barrel revolution with said fuel port; a relatively stationary housing member fitting around said first barrel and having an exhaust port; said first barrel having an exhaust passageway from each cylinder with a discharge port positioned to register with said housing port once each barrel revolution; fuel igniter means in each cylinder; an electrode extending externally of each igniter; a relatively fixed electrode past which said igniter electrodes travel; and a source of current interconnected with said electrodes; said fuel supply means comprising a passageway through at least one of said crank legs, and said

fuel discharge port being through a wall of that leg; said one leg of the crank having a passageway therethrough leading from said fuel supply means; and said fuel supply discharge port being in said first leg communicating with said passageway therein; and means creating atmospheric or above pressure in said leg passageway; means supplying oil to each of said other barrel cylinders; and oil conducting means through the pistons of both barrels and said interconnecting means, whereby the pistons in said other barrel serve as oil pumps to deliver oil to the upper ends of the pistons in said one barrel.

12. An engine comprising an L crank fixed in position; a barrel revolvably mounted on one leg of the crank; a second barrel revolvably mounted on the other leg of the crank; each of said barrels being provided with a common number of cylinders opening at adjacent ends of the barrels; a piston in each cylinder of each barrel interconnected at substantially right angles one with another; fuel supply means having a discharge port; a transverse passageway entering each cylinder of said first barrel and having a port registerable once each barrel revolution with said fuel port; a relatively stationary housing member fitting around said first barrel and having an exhaust port; said first barrel having an exhaust passageway from each cylinder with a discharge port positioned to register with said housing port once each barrel revolution; fuel igniter means in each cylinder; an electrode extending externally of each igniter; a relatively fixed electrode past which said igniter electrodes travel; and a source of current interconnected with said electrodes; said fuel supply means comprising a passageway through at least one of said crank legs, and said fuel discharge port being through a wall of that leg; said one leg of the crank having a passageway therethrough leading from said fuel supply means; and said fuel supply discharge port being in said first leg communicating with said passageway therein; and means creating atmospheric or above pressure in said leg passageway; and gear means drivingly interconnecting said barrels; and means delivering fuel under pressure into said fuel conducting means.
